UNITED STATES PATENT OFFICE.

JOHN CHARLES WILSON, OF LONDON, ENGLAND, ASSIGNOR TO SAMUEL NORRIS, OF SAME PLACE.

IMPROVEMENT IN ROTARY ENGINES.

Specification forming part of Letters Patent No. 127,943, dated June 11, 1872.

I, JOHN CHARLES WILSON, of London, England, have invented an Improved Rotary Engine, of which the following is a specification:

My invention relates to a revolving or rotary engine, which will serve also as a pump or a liquid-meter.

Description of the Drawing.

Figure 1 is a transverse central section of a rotary engine constructed according to my invention. Fig. 2 is a longitudinal section on the line *x x*, Fig. 1. Fig. 3 is an end view of one of the covers of the external fixed cylinder. Figs. 4 and 5 are a plan and section of the piston-slides. Fig. 6 is a section through the ports. Fig. 7 is an end elevation of the said engine. Fig. 8 is a longitudinal section, showing a peculiar expansive arrangement for a rotary engine. Fig. 9 is a transverse section on the line *y y*, Fig. 8. Fig. 10 is a side elevation of Fig. 9. Fig. 11 is a transverse section on the line *z z* of Fig. 10.

In revolving engines and pumps with a concentric internal revolving cylinder or piston there is a part of the external fixed cylinder which is eccentric to the internal revolving cylinder and touches it at a certain point. This part, which is called the large cam, acts as a base to the propelling power, and serves to stop the connection between the exhaust and the pressure sides of the engine or pump. This large cam I construct in one solid piece with my external fixed cylinder, for the following reasons: First, I thereby insure the equal expansion and contraction of the metal of this cam with that of the external cylinder, which is of importance in these engines, as they are fitted metal to metal, and any unequal expansion or contraction of their parts must cause either leakage or friction, and thus detract from the efficiency of the machine. Second, I avoid the expense of fitting in, which is considerable. I bore out or otherwise form the working surface of this large cam at the same time as that of the external fixed cylinder, of which it forms a part.

A is the large cam. (See especially Figs. 1 and 2.) I construct the ports for the ingress or egress of the steam, water, or other fluid to extend nearly the whole length across the ex-

ternal fixed cylinder, and as narrow as possible in the other direction, giving an area of a little more than that of the annular space between the external fixed cylinder and the internal revolving cylinder or piston. My reason for adopting this mode of construction, instead of making the ports wide and cutting away a large portion of the large cam *A*, is that I avoid that unequal wear of the outer edges of the piston-slides *D*, Fig. 1, which takes place when there is a large space cut out of the external fixed cylinder in the direction of their motion. *C* is the internal revolving cylinder or piston; *B*, the external fixed cylinder; and *E*, the annular space between them. As the large cam *A* is eccentric to the revolving piston *C*, it will be observed that the piston-slides *D* travel outward and inward through the space *E* as they pass over the surface of the said cam *A*. It is desirable while they are so traveling that the pressure and exhaust should be equal on both sides of them to avoid friction, which would result from pressure on either side of the grooves in which they work. To accomplish this object I construct recesses or projections *f* in the cover or covers of my external fixed cylinder, at the end or ends of the said piston-slides, which recesses allow the steam, water, or other fluid in a state of pressure or exhaust to pass around the end or ends of the said piston-slides, and so render equal the pressure on both sides of them. *f f*, Fig. 3, are the said recesses. Another advantage of this mode of construction is that as the piston-slides have no pressure outward at their ends they are not worn unequally by my recesses at these parts.

I guide the piston-slides *D* in their motion outward and inward by two small cams—one attached to each cover of the external fixed cylinder. I thereby insure a wide base and steady motion for the piston-slides, combined with a large wearing surface, and one which is easily oiled. *G G* are these small cams. Instead of these cams, springs to press the piston-slides outward may be used; but I prefer the cams, as being more certain and steady in their action.

I construct the piston-slides *D* in the following improved manner: Instead of making them with the whole of their surfaces on each side

planed and fitted very exactly, as they require to be, to the grooves in which they work, I construct them with recesses in their surfaces, as shown in Figs. 1, 4, and 5, leaving only narrow raised portions which have to be fitted in, and I thereby reduce materially the cost of construction. Furthermore, the inner recess, which is always within the groove, being filled with any suitable lubricating material, acts as a lubricator to the surface of the groove, and thus reduces the friction of the slides in their movement outward and inward. Moreover, by providing the outer recess with a shoulder upon the inside only, the following important result is obtained: The centrifugal force of these piston-slides at the usual speed of the engine is very great, and necessarily tends to cause friction against the surface of the external fixed cylinder; but the pressure of steam or other fluid used in the machine against this single shoulder on the outer recess tends to press my piston-slide inward, and so acts as a counter-balance to the centrifugal force; and it is obvious that according as this shoulder is made deeper or narrower so may the centrifugal force be counteracted to any desired extent. d^1 and d^2 are the said recesses in the piston-slides.

A great objection hitherto to all revolving engines has been the great consumption of steam (and fuel) in proportion to the power developed, there having been in them little or no expansion of the steam which issues through the exhaust-port at the original pressure. It is not convenient in these engines to use eccentrics and the usual cut-off-valve gear, on account of the great speed at which they work.

I construct my revolving or rotary engine with a special expansive arrangement, as follows: I use two or more cylinders, either placed end to end on the same shaft or detached. The cylinders of different sizes exhaust one into the other, commencing with the smallest and ending with the largest; by these means I obtain gradual expansion to any extent desired without the use of complicated valve machinery. Take, for instance, an engine of nine inches diameter, in which I wish to expand the steam four times. I construct the first cylinder, say, two and one-half inches wide, giving an area of piston-slide, say, of 1.6375 square inches, which has on it the full pressure of steam in the boiler; then I construct a second cylinder, say, nine inches wide, with an area of piston of, say, 6.75 square inches, or four times greater, into which the first cylinder exhausts, and the steam is thus expanded from one to four, or reduced to about one-fourth of its original pressure. A wider cylinder or more and wider cylinders may be added to expand further. I have described the above as if the cylinders were all of one diameter, but that is not necessary so long as an increased area of piston-slide is given. I prefer, however, to make them of the same diameter and of different lengths.

Figs. 8, 9, and 10 show my revolving expansive

engine with two cylinders placed end to end on the same shaft, B^1 being the smallest cylinder, and B^2 the largest. H is the steam-pipe from the boiler into B^1 . I is the exhaust-pipe from B^1 into B^2 , and K is the exhaust-pipe which may conduct the steam from B^2 either into the atmosphere or a condenser. The opening or shutting of a simple cock or valve on the pipe H is all that is necessary to start or stop these engines. It will be observed the first cylinder B^1 becomes in fact a measure of the steam used at boiler pressure. I make these engines either condensing or non-condensing; in the former case the exhaust from the last or longest cylinder simply passes into a condenser in the usual manner, the said condenser being conveniently exhausted by a detached revolving air-pump. In constructing these expansive revolving or rotary engines I keep the piston-slides D of the various cylinders all in one horizontal line. I prefer to construct the details of these expansive revolving engines in the manner shown in Figs. 1, 2, 3, 4, 5, 6, and 7; but other descriptions of revolving or rotary engines may be adapted to work expansively in a similar manner.

When a reversing-engine is required, I construct the same with a slide-valve on the top of the first or smallest cylinder, which slide-valve covers the two steam-ports with an exhaust-port between them. By simply moving this valve to make the port b^1 communicate with the boiler, as shown, the engine will revolve in the direction of the arrow 1; but by moving it so as to make the port b^2 communicate with the boiler, (as shown in the dotted lines,) the engine will revolve in the direction of the arrow 2. The exhaust-port b^3 communicates with the valve-chest of the second cylinder of the engine, entering it in the same way as the pipe H is shown to enter this first valve-chest. In the valve-chest of this second cylinder there is a second slide-valve precisely similar to the above, which is moved at the same time and in the same manner by any convenient mechanical appliance. The exhaust-pipe of the second cylinder either discharges into the atmosphere or into a condenser, or into the valve-chest of a third cylinder, if more expansion is required, this third cylinder being fitted with another similar slide-valve, and so on. A throttle-valve of the usual construction may be placed in the exhaust-pipe, the said valve being attached to a governor. By opening or closing this valve by means of the governor the speed of the engine is regulated in a better and more efficient manner than if the valve were placed in the steam-pipe, there being no wire-drawing of the steam; and as there is no fly-wheel on this revolving engine there is no objection to thus throttling the exhaust. When the said revolving engine is used as a pump the throttle-valve arranged in this manner will make it self-regulating in regard to the quantity of water delivered. Any suitable valve or cock, acting easily, without friction, is placed on the delivery-pipe of the pump,

and attached to a float, which rises or falls (and opens or shuts the valve) along with the water in the cistern or boiler which is being supplied. The pump, therefore, revolves at a speed proportioned to the opening of this valve, the steam being constantly on the engine ready to act whenever the said valve is opened. By providing the said pump with a train of wheels which receive their motion from the main-shaft, and are connected with pointers on the face of an index or indexes, it becomes an efficient fluid-meter.

These engines may be driven either by steam, water-power, or hot-air, or may be employed to pump air or gas as well as water, and may be either exhausting or compressing.

Claims.

1. The piston slide D provided with grooves d d' , substantially as and for the purpose set forth.
2. The cylinders B¹ B² of different sizes, and their pistons and slide-valves, arranged substantially as and for the purpose set forth.
3. The combination of the inner revolving cylinder C with the cams G G and recesses f f in the heads, substantially as and for the purpose specified.

JOHN C. WILSON.
